CLAIM

The ornamental design for a storage drawer for coffee capsules, as shown and described.

DESCRIPTION

FIG. 1 is a top perspective view of a storage drawer for coffee capsules showing my new design;

FIG. 2 is a top view thereof;

FIG. 3 is a bottom view thereof;

FIG. 4 is a left side view thereof, a right side view being a mirror image of the left side view;

FIG. 5 is a front view thereof;

FIG. 6 is a rear view thereof; and,

FIG. 7 is a bottom perspective view thereof.

The broken lines depict portions of the storage drawer for coffee capsules that form no part of the claimed design.

1 Claim, 7 Drawing Sheets
